UNITED STATES PATENT OFFICE.

THOMAS F. LAMB, OF NEWARK, OHIO, ASSIGNOR TO THE AMERICAN BOTTLE COMPANY,
OF NEWARK, OHIO, A CORPORATION OF OHIO.

BOTTLE-HANDLING DEVICE.

1,116,081.

Specification of Letters Patent.

Patented Nov. 3, 1914.

Application filed March 17, 1913. Serial No. 754,763.

To all whom it may concern:

Be it known that I, THOMAS F. LAMB, a citizen of the United States, residing at Newark, in the county of Licking and State of Ohio, have invented certain new and useful Improvements in Bottle-Handling Devices, of which the following is a specification.

My invention relates to an apparatus designed for use as an adjunct to a bottle-blowing or molding machine, and the main object of the invention is to provide a simple and convenient apparatus on which freshly made bottles may be placed in suitable and convenient order for subsequent removal by a workman with the usual paddle to the annealing oven or leer. Where the freshly made bottles are removed manually in succession from the molds of the bottle-forming machine and placed thence upon an ordinary table or platform, there is no certainty or exactness as to their relative arrangement, and they are frequently, through careless handling, set so close together that they are liable to adhere to each other and are also in constant danger of being accidentally upset or knocked off the receiving table.

The device of my invention is designed to eliminate these defects through the provision of an apparatus wherein the bottles, as they are successively removed from the bottle-forming machine, are placed in fixed and predetermined positions in which they cannot accidentally stick together or be upset, and in which they are suitably arranged for removal to the annealing oven by the usual workman's paddle which takes up a plural-ity of bottles arranged in a straight row.

The chief novel feature of the invention resides in the provision of a plurality of pockets or wells formed in a straight row in a temporary bottle-holder, each of said wells or pockets having a vertically movable lifter therein the upper end or head of which forms a bottle-seat, together with means for simultaneously elevating the heads forming these bottle-seats to the tops of the wells or pockets as the bottles are to be removed by the usual paddle to the leer. In the preferred form of the invention, herein illustrated, the device employs a plurality of such rows arranged in stepped relation, so that the bottles deposited therein have a limited rest period in which they can harden

beyond the sticking point, and also so that one workman can be filling one row of pockets while another workman is transferring the bottles from another row.

The device of my invention, its mode of use, and the advantages secured thereby will be more readily understood when considered in connection with the accompanying drawings which illustrate one practical embodiment of the invention, and in which—

Figure 1 is a front elevation of the completed apparatus as viewed from the left of Fig. 2. Fig. 2 is a side elevation as seen from the right of Fig. 1. Fig. 3 is an enlarged vertical section through one of the individual bottle-holders of the device, showing a freshly made bottle seated therein. Fig. 4 is a cross sectional detail on the line 4—4 of Fig. 1. Fig. 5 is a fragmentary top plan view.

Referring to the drawings, 10 designates as an entirety a skeleton base-frame, on which are mounted in parallel relation three upright rectangular frames 11, 12 and 13 of different heights, as clearly shown in Fig. 2. The frames 11, 12 and 13 are rigidly connected at their upper ends by stepped bars 14.

The parts thus far described constitute a general supporting and containing frame for three sets of bottle-receiving and ejecting devices, which are structural duplicates, and the component parts of which will, for the sake of brevity, be identified by the same reference characters.

Extending between and supported by the side bars 14 are three racks each comprising a pair of parallel angle bars 15 rigidly united and spaced at their ends by clips 16 (Fig. 5). Removably seated side by side upon the angle bars 15 and spanning the space therebetween are a series of blocks 17, each of which, as best shown in detail view Fig. 3, is formed with a central pocket or well 18 in the bottom of which is an aperture 19. The pocket or well 18 is of a size to loosely fit a bottle such as 20 set therein; and within the pocket is a lifter herein taking the form of a plunger-head 21 that has a loose sliding fit within the pocket and a plunger-stem 22 extending through the aperture 19 in the bottom thereof. In the lower end of the plunger-stem 22 is a screw 23 affording a simple and convenient means of nicely regulating the extent of upward

stroke of the lifter through the device hereinafter mentioned.

Secured to the inner sides of, and extending between the side members of each of the vertical frames 11, 12 and 13 are a pair of inwardly bowed horizontal frame pieces 24 that, as best shown in detail view Fig. 4, form supports for a vertical slideway herein shown as made up of a relatively wide vertical plate 25 secured to the frame pieces 24 and a pair of narrow strips 26 secured to and spaced from the plate 25 by bolts 27. Mounted within the slideway thus formed is a cross-head 28, from which a pin 29 extends through the vertical slot formed between the inner edges of the strips 26. Rigidly secured to the cross-head 28 is an upwardly extending V-shaped yoke 30, the upper ends of the arms of which are connected by a horizontal bar 31 so positioned that it lies directly beneath the lower ends of the lifters that are mounted in the pockets or wells 18. Pivoted on the pin 29 is a downwardly extending link 32, the lower end of which is pivotally connected to a foot-lever 33, this latter being pivoted between its ends on a cross-rod 34 of the base-frame 10, and provided at its outer end with a suitable pedal 35 adapted to be depressed by the foot of the operator to thereby raise the lifter-bar 31 that, in turn, engages and actuates the stems of the bottle-lifters contained within the pockets 18.

As shown, the three groups of bottle-receiving and elevating devices carried by the supporting frame are all independent of each other in respect to their operation; but they are assembled in convenient relation in a single supporting or carrying frame, and are well adapted for manual coöperation in forming not only convenient means for receiving and positioning the bottles in a safe manner for subsequent transfer by the workman's paddle to the annealing oven, but also for affording a sufficient interval or period of rest between the time they are removed from the bottle-forming machine and the time when they are transferred to the annealing oven to allow the bottles to harden beyond the sticking or denting point.

In the practical operation of the device, the same is positioned adjacent to a bottle-making machine of the well known rotary type, and the machine attendant, as the bottle molds successively open, grasps the necks of the bottles with his tongs and manually sets them in the pockets 18, filling the pockets of one row in order and then similarly proceeding to fill the pockets of the second and third rows. While the machine attendant is filling the pockets of one row, the oven attendant, with his paddle, approaches the machine, and placing his foot upon the pedal 35 pertaining to a previously filled row, depresses said pedal and thereby

simultaneously raises all of the bottles of that row to substantially the level of the upper surface of the blocks 17, and, tipping the entire row of bottles onto his paddle, removes his foot from the pedal, allowing the bottle-lifters to drop, and transfers the bottles to the annealing oven, thus emptying the row of pockets for re-filling by the bottle-machine attendant. The provision of the wells or pockets insures not only the uniform spacing of the bottles and the positioning thereof in a straight row most convenient for subsequent handling by the oven attendant, but it also prevents danger of the soft bottles sticking together as well as danger of accidental overturning of the bottles during the transfer from the bottle-forming machine to the oven, thus greatly reducing the extent of waste heretofore involved in the manufacture of bottles as compared with the present extensive practice of merely setting the freshly made bottles in more or less irregular order upon a table for subsequent transfer to the leir.

I claim—

1. In a bottle-handling device, the combination of a frame, a plurality of parallel rows of bottle-holders carried thereby, each of said bottle-holders having a bottle-receiving pocket formed with an apertured bottom wall, bottle-lifters slidably fitted within said pockets and having depending stems extending through said apertures, and a plurality of independently operable devices for elevating the bottle-lifters of the several rows, respectively, each of said elevating devices operating to simultaneously raise all the bottle-lifters of its row.

2. In a bottle-handling device, the combination of a frame, a plurality of parallel rows of bottle-holders mounted in stepped arrangement on the upper end of said frame, said bottle-holders each having a bottle-receiving pocket formed with an apertured bottom wall, bottle-lifters slidably fitted within said pockets and having depending stems extending through said apertures, a plurality of independent vertically movable lifting frames mounted beneath the several rows of bottle-holders respectively, and foot levers connected to and operating the respective lifting frames.

3. In a bottle-handling device, the combination of a main frame, a row of bottle-holders mounted on the upper end of said frame, each of said bottle-holders having a bottle-receiving pocket formed with an apertured bottom wall, bottle-lifters slidably fitted within said pockets and having depending stems extending through said apertures, a vertically movable lifting frame mounted on said main frame beneath said row of bottle-holders, a foot lever for actuating said lifting frame and a pivoted link connecting said frame and lever.

4. In a bottle-handling device, the combination of a main frame, a row of bottle-holders mounted on the upper end of said frame, each of said holders having a bottle-receiving pocket formed with an apertured bottom wall, bottle-lifters slidably fitted within said pockets and having depending stems extending through said apertures, a slide-way on said main frame, a cross-head engaging said slide-way, a lifting frame connected to said cross-head and having a horizontal top member extending beneath the stems of said bottle-lifters, and a foot lever connected with and actuating said cross-head.
5. In a bottle-handling device, a temporary holder for freshly blown bottles consisting of a block having a pocket or well formed therein with a centrally apertured bottom wall, and a bottle-lifter having a head forming a bottle-seat slidably mounted within said pocket and a depending stem extending through said aperture in the bottom wall of the pocket.
- 20 6. In a bottle-handling device, the combination of a main frame having at its upper end a pair of parallel horizontal inwardly facing angle-bars, a series of independent bottle-holders comprising blocks supported side by side at their ends on said angle-bars and each having a pocket or well formed therein with a centrally apertured bottom wall, bottle-lifters having heads forming bottle-seats slidably mounted within said pockets and depending stems extending through said apertures in the bottom walls of the pockets, screws in the lower ends of said stems for adjusting the operative lengths of the latter, a vertically reciprocable lifter-frame having at its upper end a horizontally disposed bar adapted to simultaneously engage the adjusting screws of said stems on its upward movement and a foot-operated means for raising said lifter-frame.
